UNITED STATES PATENT OFFICE.

ALBERT C. DIEHL, OF PENSAUKEN, NEW JERSEY, ASSIGNOR TO VICTOR TALKING MACHINE COMPANY, A CORPORATION OF NEW JERSEY.

SOUND-BOX FOR SOUND-REPRODUCING AND SOUND-RECORDING MACHINES.

1,350,595.

Specification of Letters Patent. Patented Aug. 24, 1920.

Application filed September 14, 1915, Serial No. 50,551. Renewed January 17, 1920. Serial No. 352,232.

To all whom it may concern:

Be it known that I, ALBERT C. DIEHL, a citizen of the United States, residing at Pensauken, Camden county, State of New Jersey, have invented certain new and useful Improvements in Sound-Boxes for Sound-Reproducing and Sound-Recording Machines, of which the following is a full, clear, and exact description, reference being had to the accompanying drawings, forming a part of this specification.

My invention relates to sound boxes for sound reproducing and sound recording machines and particularly to the supporting mechanism upon which the stylus bar is mounted to oscillate in transmitting vibrations to and from the diaphragm through the stylus bar, and my invention has for its objects, among others, to provide a construction in which the stylus bar may be put under tension, and in which the degree to which such tension is applied may be adjusted, regulated and controlled to a nicety and accuracy heretofore unattained, without substantially increasing the frictional resistance to the free vibration of the stylus bar; to prevent the compression or tension member from vibrating independently of its vibration by and with the stylus bar about the oscillatory axis of the stylus bar; to so arrange the compression or tension member that its mass is disposed substantially equal on opposite sides of the axis of oscillation of the stylus bar and thus position it in a balanced relation with respect to the axis of oscillation of the stylus bar; to improve the quality of the sound reproduced and to more truly record sound by avoiding any liability of chatter or vibration in the parts of the sound box construction; and to permit the stylus bar to move with the least restraint possible in recording or reproducing sound.

Other objects of my invention are to simplify and reduce the weight of the elemental parts of the sound box, particularly of the stylus bar mounting and to avoid any variations in resistance to the swinging or oscillatory movement of the stylus bar.

Other objects of my invention will appear in the specification and claims below.

To these ends my invention consists generally of the combination of elements, and also of the specific construction of some of the elements in lesser combination of them,

as hereinafter described and pointed out in the appended claims.

Referring now to the drawings forming a part of this application, and in which the same reference characters are used to designate the same parts throughout the various views, Figure 1 is a side elevational view, partly in section, of a sound box having a stylus mounted in accordance with the invention of this application; 60

Fig. 2 is a front elevational view of the construction shown in Fig. 1;

Fig. 3 is a bottom view of the construction shown in Fig. 1;

Fig. 4 is an enlarged longitudinal sectional view of a portion of the stylus bar and a longitudinal view of the mounting therefor, said section being taken on the line 4-4 in Fig. 3; 70

Fig. 5 is a longitudinal sectional view enlarged similarly to Fig. 4, of a portion of the stylus bar and the mounting therefor, said section being taken on line 5-5 of Fig. 2. 75

Fig. 6 is a further detailed view showing 80 the surface on the end of the adjustable screw stud and the surface at the bottom of the recess in the resilient member as having radii of curvatures greater than the radius of the curvature of the bearing ball 85 coöperating therewith and interposed between said surfaces;

Fig. 7 is an enlarged side elevational view of a portion of the stylus bar prior to the attachment thereto of the spring member; 90

Figs. 8, 9 and 10 are detailed views, illustrative of the way in which the spring member is made; and

Fig. 11 is a view similar to Fig. 6 but showing a modified construction in which 95 the bottom of the recess in the spring member is conical in shape as distinguished from spherical.

Referring first to the form of the invention as illustrated in Figs. 1 to 10 of the drawings, there is provided a support 1 rigidly secured in any manner, as by screws 2-2, to the outer surface of a sound box casing 3 within which is mounted in any approved manner the usual diaphragm 4. 105 This support is preferably formed so as to provide two blocks or lugs 5-5 disposed symmetrically with respect to a plane passing through the center of the diaphragm. Near the outer and free ends of said blocks 110

or lugs 5 are provided a pair of alined screw studs 6—6, each threaded through the block or lug in which it is mounted and each provided with a lock nut 7—7 by means of 5 which said studs 6—6 may be rigidly locked in place after having been adjusted to the desired position.

The upper end of the stylus bar 8 is attached to the center of the diaphragm in 10 any approved manner, as, for instance, by the screw 9, and the wax or cement 10 as is common in sound box construction. The stylus bar 8 is provided on its outer end with the usual socket within which may be 15 inserted the stylus or needle 11 and is provided with the usual set screw 12 for securely clamping the stylus or needle 11 in the stylus bar.

Intermediate the ends of the stylus bar 8 20 is preferably provided a larger portion or section 13, the outer surface of which is provided with a groove or channel 14 which is preferably rectangular in shape transversely of the groove and cylindrical in 25 shape longitudinally thereof to provide a seat within which a spring, compression or tension member 15, more particularly described below, may be rigidly secured. Upon each side of the channel 14 and formed 30 thereby are the lugs 14' 14' which clamp the member 15 as later referred to.

The spring, compression or tension member 15 is preferably made substantially 35 annular in shape and rectangular in cross-section and said spring member is in transverse cross-section of the size and shape of the channel 14 in the larger section 13 of the stylus bar 8. The said member 15 is of integral construction and is preferably 40 made by first forming a steel ring or annulus 16 (as shown in Fig. 8) and then cutting or milling a recess 17 on the inside thereof to form a resilient web or connecting portion 18. The web is then forced and bent 45 inwardly in any suitable manner as by a "swaging" process to form a resilient web 19, the exterior surface of which, instead of being convex is concave. If so desired, the outer surface of the web 19 may be 50 made more concave than the web 18 is convex; that is to say, the radius of curvature of the concave surface of the web 19 of the finished member shown in Fig. 11 may be less than the radius of the curvature of 55 the convex surface of the web 18 prior to the "swaging" process and as illustrated in Fig. 10. When so constructed, the whole ring or annulus 16 is preferably slightly reduced in diameter during the "swaging" 60 process to compensate for the consequent lessening of the distance between the thicker portions of the member on the other side of the web.

The compression member 15 thus formed 65 is afterward rigidly secured to the stylus

bar preferably by "sweating" the said member into the groove or channel 14 and between the lugs 14' 14' which serve to clamp the member 15 with its relative stiff resilient portions 20—20 symmetrically disposed 70 and arranged to the stylus bar 8 and with respect to the web 19. These resilient portions 20—20 are preferably substantially semi-circular in shape longitudinally considered.

Either before or after the compression member 15 has been thus secured to the stylus bar, it is provided on the opposite sides thereof with alined recesses 21—21, the line between said recesses preferably intersecting the axis on the stylus bar at that point. In the embodiment of the invention illustrated in Figs. 1 to 10, the recesses 21 are provided with spherical surfaces 22, the radii of which surfaces are greater than the 85 radius of the ball 23 arranged to be seated therein. The inner end of each stud 6—6 is also preferably provided with a recess 24, the surface of which is preferably spherical and of greater radius than the radius of the 90 ball 23. In each recess 21 of the compression member 15 is provided a ball 23 against which the recessed end 24 of the coöperating or coacting screw stud 6 is adapted to bear when the device is assembled in the manner 95 shown in Figs. 1 to 4.

By virtue of the fact that the radii of curvature of the recesses 21 and 24 in the compression member and screw studs are respectively greater than that of the balls 100 23 interposed between them, theoretically there is but a single point of contact between the ball 23 and its coöperating stud 6, and between each ball and the compression member 15, and as these points of alinement are 105 substantially coincident with the axes of the alined studs 6—6, the stylus bar oscillates about these points of contact as an axis.

In the modification shown in Fig. 11, the bottom 22' of the recesses 21' in the compression member 15 are conical, as distinguished from spherical and the stylus bar will oscillate about the points of contact between the studs 6 and the balls 23, but the conical surfaces of the recesses 21' will hold 115 the balls in alinement with the axes of the alined screws or studs 6.

If the web 19 were to be omitted then the free ends of the portions 20—20 of the compression member would have a tendency to 120 vibrate independently in directions other than that in which the stylus bar itself vibrates, and such an independent vibration of said portions of said members would tend to produce false vibrations in the stylus bar 125 and in the diaphragm attached thereto. If, on the other hand, the said portions 20—20 were to be rigidly connected together as by making the ring or loop continuous and of substantially the same size throughout in 130

cross-sectional area, such independent vibration of said parts of the compression member might be obviated, but the said portions 20-20 would not be relatively freely movable toward and away from each other under the compressive action of the alined studs 6-6. Thus the relatively free movement of the portions 20-20 toward and away from each other for the adjustment 10 of the tension thereon between the alined studs 6-6 would be destroyed. When, however, the portions 20-20 are connected together by the thin resilient web 19 integral with said portions, this web does not substantially interfere with or prevent the controlled relative movement of said parts 20-20 toward and away from each other under the adjustive action of the screws 6-6, but tends to absorb, prevent or control 15 any free or independent vibration of the said parts 20-20 which are of full cross-section, and modifies or affects the flexibility of the said portions 20-20. The construction is such that the compression member 25 has portions having different degrees of resilient flexibility, each of which mutually modifies the flexibility or resiliency of the other part or parts of the member. The device, therefore, embodies a construction in 30 which the tension, to which the resilient compression member is subjected, may delicately be adjusted without the liability of having in the reproduced sound undesirable sounds.

35 With the parts, arranged, constructed and assembled in the manner above set forth, the spring or compression member 15 encircles the stylus bar and is disposed in a plane substantially normal to the longitudinal axis 40 of the stylus bar at its point of attachment thereto. The length of the thin resilient web 19 is substantially the same as the length of the groove 14 in the stylus bar in which the resilient member 15 is seated, and the 45 weight of the parts 20-20 of the resilient member 15 on either side of the axis of oscillation of the stylus bar is substantially equal with the result, therefore, that the effective portions of the compression member are disposed in a substantially balanced relation 50 with respect to the axis of oscillation of the stylus bar.

With the stylus bar substantially vibrating upon a single point on a spherical surface, it must be obvious that said point of contact is very much more durable and uniform in its action than an ordinary conical pivot point would be; and that the mounting will be substantially free from 55 any cramping or similar action should the studs or screws 6-6 be not exactly in perfect alinement with each other, although, of course, it must be borne in mind that in making the constructions illustrated in the 60 drawings of this application the said ad-

justing screws 6-6 and the recesses in the compression member arranged to receive the balls are made in as nearly perfect alinement as careful machine work permits.

This construction also makes it possible 70 to completely obviate the chatter or rattle of the said parts of the stylus mounting during the operation thereof because of the manner in which the surfaces engage and the ability to put the stylus bar under what- 75 ever tension may be found necessary or desirable without unduly increasing the resistance to the free oscillation of the stylus bar upon its virtual pivot.

Having thus described this invention 80 what is claimed and is desired to protect by Letters Patent of the United States is:

1. In a sound box, the combination of a stylus bar and a transverse resilient loop rigidly secured to said stylus bar, and having portions varying from each other in resilience flexibility.

2. In a sound box, the combination of a stylus bar, a flexible member surrounding said stylus bar and moving therewith, said flexible member having a portion which modifies the flexibility of other portions of said member.

3. In a sound box, the combination of a stylus bar, a flexible member through which said stylus bar passes, disposed in a plane transverse to the longitudinal axis of said stylus bar and having a reduced portion to modify the flexibility of other portions of said flexible member.

4. In a sound box, the combination of a stylus bar, a flexible member encircling said stylus bar and moving therewith, and pivotal bearings about which said stylus bar and said member are vibratable, said flexible member being extended upon both sides of the pivotal bearings and the weight thereof upon each side of said bearings being substantially equal whereby said flexible member in its oscillation about the pivotal bearings tends to move with balanced motion.

5. In a sound box, the combination of a stylus bar, a continuous flexible member rigidly secured to said stylus bar and extending therearound and transverse thereto, a bearing for said flexible member about which said flexible member and stylus bar are arranged to vibrate, the axis of vibration of said stylus bar and said flexible member being disposed so that portions of both members are upon opposite sides of said axis and at some distance therefrom whereby the movement of the stylus bar and flexible member is a substantially balanced motion due to the disposition of weight of parts upon both sides of the axis.

6. In a sound box, the combination of a stylus bar and a resilient compression member disposed in a plane transverse to the

longitudinal axis of said bar, said compression member having a portion reduced in cross-section to provide a resilient member which joins the adjacent portions of the full cross-section portions of said resilient member, whereby said reduced cross-section prevents independent movement of the portions of full cross-section adjacent thereto.

7. A sound box of the class recited, comprising in combination a casing, a diaphragm, a stylus bar connected thereto and having spaced lugs projecting therefrom, a ring member extending around said stylus bar and clamped thereto between said lugs, and provided with diametrically opposite recesses, bearing balls, one in each of said recesses, respectively, wings or projections extending from said casing to a position adjacent said ring member, and oppositely disposed screw studs mounted in said wings and having cupped ends adapted to engage said bearing balls.

8. In a sound box, the combination with a stylus bar, of a compression member, rigidly secured to and encircling said stylus bar and having a resilient reduced portion, a pair of alined studs adjustable toward and away from each other and arranged to compress said resilient member between them.
9. In a sound box, the combination with a stylus bar, of a compression member forming a part of said stylus bar and having resilient portions disposed on opposite sides of said stylus bar, a pair of alined studs adjustable toward and away from each other and arranged to compress said resilient portions between them, each of said resilient portions being provided with a recess in alinement with said studs, and a pair of balls, each seated in one of said recesses respectively and in engagement with the end of one of said studs.

10. In a sound box, the combination with a stylus bar, of a compression member forming a part of said stylus bar and having resilient portions disposed on opposite sides of said stylus bar, a pair of alined studs adjustable toward and away from each other and arranged to compress said resilient portions between them, each of said portions being provided with a recess in alinement with said studs, and a pair of balls, each seated in one of said recesses respectively and in engagement with the end of one of said studs, the inner ends of said studs being recessed to provide a spherical surface of a greater radius than the radius of the ball coöperating therewith.

11. In a sound box the combination with a stylus bar, of a compression member secured to said stylus bar and having resilient members disposed on opposite sides of said stylus bar, a pair of alined studs adjustable toward and away from each other and arranged to compress said resilient members

between them and means connecting together the free ends of said resilient members to prevent the independent vibration of said portions.

12. In a sound box, the combination with a stylus bar, of a compression member secured to said stylus bar and having resilient members disposed on opposite sides of said stylus bar and arranged substantially concentric with the longitudinal axis of said stylus bar, of a pair of alined studs arranged to spring said resilient members toward each other and a resilient web connecting together said resilient members.

13. In a sound box, the combination with a stylus bar, a compression member attached to and forming a part of said stylus bar and having resilient members disposed on opposite sides of said stylus bar and arranged substantially concentric with the longitudinal axis of said stylus bar, of a pair of alined studs arranged to spring said resilient members toward each other and a resilient web integral with and connecting together said resilient members.

14. In a sound box, the combination with a stylus bar, of a continuous compression member forming a part of said stylus bar with its plane normal to the axis of said stylus bar, a pair of alined studs adjustable toward and away from each other, said compression member moving with said stylus bar and exerting its action against said studs with the same degree in all positions, said compression member being formed at one portion thereof with a reduced part extending between two adjacent unreduced parts.

15. In a sound box, the combination with a stylus bar, of a continuous compression member disposed in a plane normal to the axis of said stylus bar and surrounding said stylus bar, and moving therewith in the vibration thereof, of a pair of alined studs adjustable toward and away from each other and arranged to compress said compression member between them.

16. In a sound box, the combination with a stylus bar, of a compression member connected thereto and a pair of alined studs adjustable toward and away from each other and arranged to compress said compression member between them, said compression member being provided with resilient portions disposed practically equally about the axis of said alined studs, said portions serving to balance the parts and the motions thereof due to the substantially equal distribution of weight of said flexible member about the axis of the alined studs.

17. A mounting for a stylus bar for sound reproducing machines, comprising a resilient ring adapted to be rigidly attached to and to surround a stylus bar, and provided with a pair of diametrically oppositely posi-

tioned recesses, and with a resilient portion forming an integral part of said ring, said portion being of considerably reduced cross-sectional area and located between 5 said recesses.

18. A mounting for a stylus bar for sound reproducing machines, comprising a resilient ring adapted to be rigidly attached to and to surround a stylus bar, and provided with a pair of diametrically 10 oppositely positioned surfaces upon which said

member is adapted to be supported for vibration, and with a resilient portion forming an integral part of said ring, said portion being of considerably reduced cross-sectional area, and being located between 15 said surfaces.

In witness whereof, I have hereunto affixed my signature this 13th day of September, 1915.

ALBERT C. DIEHL.
